UNITED STATES PATENT OFFICE.

CLARENCE H. KELSEA, OF BELMONT, MASSACHUSETTS, ASSIGNOR TO PETER GRAY & SONS, INC., OF CAMBRIDGE, MASSACHUSETTS, A CORPORATION OF MASSACHUSETTS.

ILLUMINATING APPARATUS.

Application filed August 18, 1923. Serial No. 658,156.

This invention relates to illuminating apparatus of that character employing an incandescent electric lamp and a reflector co-operating therewith.

5 One object of the invention is to provide an illuminating apparatus of the character specified in which the reflector and the socket for the incandescent lamp are in fixed relation to the housing and in non-adjustable relation to each other, with the focus of the reflector in a plane through the center of the lamp filament.

Another object of the invention is to provide an illuminating apparatus of novel 15 and simplified construction in respect to the electrical connections employed in connection with the operating of the apparatus, with attending increase in efficiency of the apparatus.

20 To these ends the apparatus is provided with a projector unit comprising preferably a housing, an electric lamp socket secured in fixed relation thereto, and a reflector insertable into the housing to be positioned with 25 relation to the said socket to initially adjust and position the reflector with respect to the lamp so that the focal point of the reflector is substantially coincident with the center of the lamp filament, and provision 30 is made for securing or locking the reflector in this position to prevent its being tampered with, and to insure that the lamp and the reflector are maintained properly focused at all times during the use of the apparatus with lamps having the same or substantially the same light center and such as are now available on the market and known as "precision lamps."

35 Provision is also preferably made for permitting the main supply wires to be directly connected to the projector unit and thereby eliminate excess wiring and connections, avoid to a large extent the liability of loose connections and joints, and increase the efficiency of the apparatus. To this end the reflector housing is preferably provided with relatively large terminal posts mounted on said housing in an accessible position and connected directly with the lamp and 40 socket and to which the supply wires may be directly connected.

45 These and other features of the invention will be hereinafter described and particularly pointed out in the claims at the end 50 of this specification.

In the drawings, Fig. 1 is a vertical central longitudinal section of an illuminating apparatus embodying the present invention, and showing the reflector in its adjusted position; Fig. 2 a side elevation of the projector unit shown in Fig. 1; Fig. 3 a longitudinal section of the projector unit showing the reflector free from the housing or unattached thereto and not in its adjusted position; and Fig. 4 a detail in rear elevation of the projector unit.

55 Referring to the drawings, the illuminating apparatus illustrated therein is provided with a projector unit comprising a housing 10, a lamp socket 12 secured in fixed 60 relation to the housing, and a reflector 14 adapted to co-operate with an electric lamp 15 when the latter is inserted into the lamp socket 12 in the manner illustrated in Fig.

65 1. As herein shown, the lamp socket 12 is 70 provided at its rear end with a flange 16 which is received and clamped between insulating plates or disks 18, 20, secured together and to the housing 10 by screws 21, see Fig. 4, and forming the rear wall of said 75 housing. The reflector 14 is insertable into the housing 10 to be capable of adjustment for the purpose of focusing it with relation to the lamp 15, and is preferably held in its adjusted position by a relatively heavy 80 coil spring 22 interposed between a bearing ring 24 for the reflector 14 and the insulating plate 20 of the rear surface or wall of the housing 10, said spring co-operating 85 with a retaining ring 26 adapted to fit into 90 the mouth of the housing 10 and against which the reflector 14 is urged by the coil spring 22. Provision is made for securing 95 the retaining ring 26 in fixed relation to the housing 10 after the reflector has been 100 properly adjusted, that is with the focus of the reflector in a plane passing through the center of the filament of the lamp 15, and as herein shown this may be conveniently 105 accomplished by soldering the ring to the housing 10, the solder being indicated by the heavy black line 28. After the reflector has been focused and secured or locked in its focused position in the manner described, the mouth of the housing is closed by the 110 usual cover glass 30 which is secured in the usual manner in its retaining ring 31, the latter being secured to the housing in any usual or preferred manner, as by the spring latch 32.

Provision is also made for simplifying the electrical connections between the lamp and the supply wires therefor, and to this end relatively large terminal posts 40, 41 are mounted directly upon the projector unit and as herein shown are extended through holes in the insulating members 18, 20, and are provided with lock nuts 42, 43 thereon for the purpose of clamping them to the insulating members 18, 20. The threaded ends of the bolts are each provided with nuts 44 between which the ends of the supply wires may be clamped in a convenient manner. One bolt or terminal post 40 is connected with the lamp socket 12 by a metal angle member 45 soldered or otherwise secured thereto. The second binding post 41 is connected to a contact member for the lamp, said contact member comprising a head 48 on the end of a rod 49 movably supported within the lamp socket by an insulating disk 50, and having its rear end extending through a hole in the insulating member 18, as shown. A spring 54 is provided for yieldingly holding the contact member 48 against the terminal 55 of the lamp. The end of the rod 49 is connected by a wire 56 to the binding post 41.

With this construction it will be observed that the single pair of binding posts 40, 41 carried by the projector unit serves for the connection of the projector unit with the main supply wires, not shown, and as a result the wiring of the apparatus is reduced to a very simple, inexpensive and highly efficient form.

It will be observed that when the apparatus is assembled ready for use, both the lamp socket and the reflector are in fixed

relation to the housing and in non-adjustable relation to each other with the lamp at or substantially at the focus of the reflector, which prevents the relations of the lamp and reflector being disturbed or tampered with by unauthorized persons after the apparatus has been delivered to the user.

Having thus described the invention, what is claimed is:

1. In an illuminating apparatus, in combination, a housing having an insulating rear wall, a non-adjustable lamp socket secured to said insulating rear wall, an electric lamp co-operating with said socket, a non-adjustable reflector within said housing with its focus in a plane passing through the filament of the lamp, a bearing ring for the rear end of said reflector surrounding said lamp socket, and a compressed spring surrounding the lamp socket and bearing against the insulating rear wall and the said bearing ring.

2. In an illuminating apparatus, in combination, a housing having an insulating rear wall provided with an opening extended through it, a non-adjustable reflector within said housing, a non-adjustable lamp socket secured to the rear wall in line with said opening, terminal posts carried by said insulating rear wall, and a spring-pressed contact member slidably in said socket within the housing and extended through the opening in the insulating rear wall and connected with one of said terminal posts, and means for connecting the lamp socket with the other of said terminal posts.

In testimony whereof, I have signed my name to this specification.

CLARENCE H. KELSEA.
